(57) CLAIM

The ornamental design for a cosmetics bottle as shown and described.

DESCRIPTION

FIG. 1 is a top perspective view of a cosmetics bottle, showing the new design;

FIG. 2 is a front elevation view thereof, wherein the rear elevation view is identical;

FIG. 3 is a left side elevation view thereof, wherein the right side elevation view is identical;

FIG. 4 is a top plan view thereof; and,

FIG. 5 is a bottom plan view thereof.

The broken lines represent portions of the cosmetics bottle that form no part of the claimed design.
